VIBRATOR

Albert C. Wilcox, Chicago, Ill.

Application April 10, 1942, Serial No. 438,377

2 Claims. (Cl. 128—52)

The invention relates to vibrators, and more particularly to a vibrator having a reciprocating massage cushion operated by an electro-magnet.

It is an object of the invention to provide an electric vibrator having a vertically disposed electro-magnet, the reciprocating core or armature of which supports a massage cushion for rapidly vibrating the same.

Another object is to provide a vibrator of the character referred to in which spring means is associated with the armature acting against the pull of the magnet.

A further object of the invention is the provision of a vibrator of this character in which the armature is swivelled within the magnet.

A still further object is the provision of such a vibrator which is adapted for the well known method of Swedish massaging.

Another object is to provide a vibrator which may be easily and readily adjusted to obtain the desired vibration.

It is still another object of the invention to provide a vibrator which is of simple and inexpensive construction and flexible in operation.

A further object is to provide a vibrator in which several types of massage cushions are easily and readily interchangeable.

Still another object is the provision of a vibrator having a massage cushion provided with expansion springs through which the operator may place his fingers for giving a Swedish massage.

The above objects together with others which will be apparent from the drawings and following description or which may be later referred to, may be attained by constructing the improved electric vibrator in the manner illustrated in the accompanying drawings, in which—

Figure 1 is an elevation of an electric vibrator embodying the invention;

Fig. 2 a vertical sectional view through the vibrator shown in Fig. 1;

Fig. 3 an end view of the massage cushion shown in Figs. 1 and 2;

Fig. 4 a longitudinal, sectional view of a modified form of massage cushion;

Fig. 5 a vertical, sectional view of a slightly modified form of electric vibrator;

Fig. 6 an elevation of the magnet and armature shown in Fig. 5; and

Fig. 7 an elevation of a modified form of shell or casing applied to the improved vibrator.

Similar numerals refer to similar parts throughout the drawings.

Referring first to the form of vibrator shown

in Figs. 1, 2 and 3, a cylindric shell 10, which may be formed of sheet metal or other suitable material, is provided for housing the electro-magnet and armature of the improved vibrator.

5 The lower end of the shell 10 may be rounded as indicated at 11, and provided with a central aperture 12, through which the armature is adapted to reciprocate, as will be later described.

A flanged cover or lid 13 is provided for covering the upper open end of the shell 10, and is arranged to be held in position upon the shell by means of the screw 14.

15 The magnet includes the inverted U-shape pole piece 15 formed of soft iron and connected to the shell 10 as by the screws 16. The magnet coil or solenoid 17 is mounted within the pole piece and the cross member 18 is connected to the lower ends of the pole piece 15 beneath the lower end of the magnet coil.

An adjusting screw 19 is threaded through the top of the pole piece 15 and a lock nut 20 is provided thereon for holding the screw in adjusted position. This adjusting screw is provided with the internal threads 21 into which the screw 14 is threaded for holding the cover 13 upon the shell.

25 The magnet coil 17 has a central vertical opening 22 therein and the reciprocating armature 23 is mounted for vertical sliding movement therein.

30 This armature has the reduced lower extension 24 slidably located through an aperture 25 in the cross piece 18 and an adjusting nut 26 is mounted thereon at a point spaced below the cross member, a compression spring 27 being located 35 around the reduced extension 24 of the armature between the cross member 18 and the nut.

A further reduced extension 28 may be formed upon the armature below the nut 26 for sliding movement through the aperture 12 in the lower 40 end of the rounded bottom portion 11 of the shell. This extension terminates in a reduced threaded portion 29 by means of which the massage cushion may be attached to the armature.

45 As shown in Figs. 1, 2 and 3, this massage cushion may include a channel-shape member 30 of stamped sheet metal or the like provided at its side edges with down turned flanges 31 and having a central threaded opening 32, or nut 33, or both, to receive the threaded lower 50 end 29 of the armature.

The sponge-rubber cushion 34 is cemented or otherwise mounted within the inverted channel-shape holder 30 and extends a considerable distance below the flanges 31 thereof.

Eyes or hooks 35 are formed at the ends of

tro-magnet within the shell including a U-shape pole piece, means detachably connecting the legs of the pole piece to the sides of the shell, a coil supported within the pole piece, a reciprocating armature mounted within the coil and extending through the lower rounded end of the shell, a massage cushion upon the lower end of the armature, an adjusting screw located through the pole piece for contact with the adjacent end of the armature to limit the throw of the armature in one direction, a lock nut for holding the adjusting screw in adjusted position, said adjusting screw being internally threaded, a removable

5 cover upon the top of the shell and an attaching screw located through the cover and engaging the internal threads in the adjusting screw for detachably securing the cover upon the shell, a cross piece connected to the lower ends of the legs of the U-shape pole piece, the armature being slidably mounted through said cross piece, an adjusting nut on the armature spaced below said cross piece and a coil spring located around the armature between said shoulder and cross piece and housed within the rounded bottom portion of the shell.

ALBERT C. WILCOX.
